UNITED STATES PATENT OFFICE.

CHARLES WILLIAM HAWKES, OF CHICAGO, ILLINOIS.

STEAM-BOILER.

No. 809,503.

Specification of Letters Patent.

Patented Jan. 9, 1906.

Application filed August 21, 1905. Serial No. 275,043.

To all whom it may concern:

Be it known that I, CHARLES WILLIAM HAWKES, a citizen of the United States, residing at Chicago, in the county of Cook and State of Illinois, have invented certain new and useful Improvements in Steam-Boilers, of which the following is a full, clear, and exact description, reference being had to the accompanying drawings, forming a part hereof.

My invention has relation to improvements in combined fire-tube and water-tube boilers; and it consists in the novel construction and arrangement of parts more fully set forth in the specification, and pointed out in the claims.

In the drawings, Figure 1 is a longitudinal middle vertical section of the boiler and furnace on the line 1 1 of Fig. 2. Fig. 2 is a half-section and elevation of the front of the boiler. Fig. 3 is a half-section and elevation of the rear of the boiler. Fig. 4 is a sectional detail showing construction and manner of drawing the flush-plug to its seat. Fig. 5 is a rear view of the plug. Fig. 6 is a front view of the plug. Fig. 7 is a sectional detail on line 7 7 of Fig. 1, showing the construction of the brick-tile for incasing the lower water-tubes. Fig. 8 is a similar section of a modified construction of tile, and Fig. 9 is a sectional detail showing a modification of a mud-drum attached to the rear water-leg.

The object of my invention is to construct a combined fire-tube and water-tube boiler which shall utilize to the best advantage the heat units of the combustion products, one which shall insure a well-defined and positive circulation of the water in the boiler, one which shall insure an even distribution of the combustion products among the surfaces to be heated, one which will insure against a too rapid deterioration of the parts exposed to the combustion products, one in which certain portions of the boiler shall be protected against direct contact with the combustion products, one in which the combustion products are directed to and caused to escape from the rear of the boiler, one which will permit of ready repair, one in which no rivet-heads are exposed to the direct action of the combustion products, thereby minimizing the danger of leakage, one into whose construction any available material may enter, such as boiler-plate proper or steel castings, one whose furnace consumes the bulk of the smoke, and one possessing further and other advantages better apparent from a detailed

description of the invention, which is as follows:

Referring to the drawings, G represents the grate; F, the fire-box; B, the bridge-wall; C, the main or lower combustion-chamber of the furnace, and C' the upper or supplemental combustion-chamber.

The boiler in the present instance is composed of three distinct members or sections— 65 viz., the upper fire-tube section a, composed of a shell traversed lengthwise by a series of fire-tubes; the lower water-tube section b, composed of a series of water-tubes, and the intermediate section constituting the upper 70 water-tube section c, likewise composed of a series of water-tubes. The water-tube sections are disposed substantially parallel to one another and at an incline to the fire-tube section which surmounts them, the inclination being upward and forward, so as to insure effective contact with the products of combustion passing from the fire-box. Depending from the rear end of the section a and passing half-way around the periphery 80 of the shell of said section a is a water-leg 1, which establishes communication with the lower rear ends of the water-tube sections b c. Encompassing the lower peripheral half 85 of the shell of the section a and depending slightly below said section is the front water-saddle 2, which establishes communication with the front end of the water-tube section c. The lower water-tube section b is extended forward and beyond the front end of 90 the section a and taps the water-tube header 3, which, as shown, is mounted on rollers 4 to allow for the necessary expansion and contraction. From the top of the header 3 lead a series of curved circulating-tubes 5, 95 the upper ends thereof tapping the shell of the section a and the front wall of the saddle 2 in a plane slightly above the upper ends of the tubes of the section c.

Extending rearwardly to a suitable point 100 beyond the bridge-wall and suspended between the series of tubes constituting the lower section b are special fire-tiles 6, which collectively incase the several tubes and form a partition-wall, which not only serves 105 to protect the tubes against direct contact with the combustion products, but to deflect said products rearwardly beyond the bridge-wall, where they are free to ascend between the tubes b to a point above. The space between the fire-tiles and tubes is preferably 110 packed with a layer of fire-clay m. The up-

per water-tube section *c* is covered with split fire-brick or equivalent material 7, preferably protected with a layer of non-conducting material 8, such as asbestos, magnesia, and the like. This covering of brick 7 constitutes a wall or partition which conjointly with the partition 6 forms a flue or conduit 9 for the products of combustion, the latter, as shown by the feathered arrows, passing forward and upward to the front of the furnace and rearwardly through the fire-tubes of the section *a*, finally entering the smoke-box or exit-flue 10, which in the present instance is at the rear end of the boiler. It may be desirable in some instances and under certain conditions to admit a portion of the gases and combustion products directly into the conduit 9 before they have passed beyond the partition 6, in which case I may perforate the bricks forming said partition, as shown in the modification in Fig. 8, where 6' represents the brick, and *p* a passage therethrough. Again, in the forms shown in the drawings the brick entirely incases the tubes; but while such total incasing of said tubes is perhaps desirable and in the majority of cases essential it is not absolutely necessary, and the brick may be so formed as to protect only the lower halves or portions of the peripheral surfaces of the tubes against the direct impact of the gases and combustion products. The front wall of the water-saddle 2 is provided opposite the ends of the tubes *c* with openings closed by the flush-plugs 11, the openings permitting the "rolling" or expanding of the ends of the tubes against the wall of the saddle which supports them. The flush-plugs are readily installed into position through the terminal hand-holes of the saddle, which are closed by plugs 12 of ordinary construction. Each flush-plug 11 is provided with a socket 13, whose face wall is provided with a T-shaped opening 14. Through the wide portion of this opening is passed the head of a T-bolt 15, after which the bolt is shifted to bring its stem into the narrow portion of the opening, the head by this time passing behind the wall of the plug, which serves as an abutment. Then with a crab or washer 16 inserted between the nut 17 of the bolt and the wall of the saddle the plug can be drawn up to a bearing by screwing the nut against the crab. After this the bolt and crab are removed, so as not to burn up under the action of the products of combustion, the plug remaining securely wedged in the conical or tapering opening in the saddle-wall which receives it. The lower overlapping edges of the opposite front and rear walls of the rear water-leg are riveted, the riveted seam resting directly on the masonry of the furnace-wall, so that no rivet-heads are exposed to the combustion products, and hence the danger of starting a leak is reduced to a minimum, Fig. 1.

The feed-pipe is represented by 18, and the dry pipe by 19. The clean-out is shown at 20. Such other conventional portions as may be shown in the drawings, but to which no reference is made, are well understood in the art and require no special reference here, as they form no part of my present invention. Where necessary a mud-drum 21 may be attached to the bottom of the rear water-leg, as shown in the modification in Fig. 9. The supplemental combustion-chamber C' (that immediately in front of the boiler-section *a*) is preferably formed of a sheet-steel casing lined with fire-brick and jacketed with asbestos, as shown. 80

The disposition of the several parts of the boiler as shown is conducive to a perfect water-circulation, the path of such circulation being indicated by the plain arrows in Fig. 1. The current from the tubes 5 serves to induce circulation from the saddle 2, and that from the saddle in turn induces circulation in the tubes 5, so that the two currents mutually assist one another, the combined currents thence passing rearwardly through the section *a*, thence downwardly through the rear water-leg 1, thence upwardly through the sections *b c*, as shown. 85 90

Having described my invention, what I claim is— 95

1. A boiler comprising a series of superposed water-tube sections, a fire-tube section surmounting the same, a water-leg connecting one end of the respective water-tube sections with the adjacent end of the fire-tube section, and independent means for connecting the opposite ends of the respective water-tube sections with the fire-tube section, the space between the water-tube sections communicating with the fire-tube section at the end opposite to the water-leg, substantially as set forth. 100 105

2. A boiler comprising a series of superposed water-tube sections, a fire-tube section surmounting the same, a water-leg connecting one end of the respective water-tube sections with the adjacent end of the fire-tube section, a smoke box or flue leading from the fire-tube section at the end adjacent to said water-leg, and independent means for connecting the opposite ends of the respective water-tube sections with the adjacent end of the fire-tube section, the space between the water-tube sections communicating with the fire-tube section at the end opposite the smoke-box, substantially as set forth. 115 120

3. A boiler comprising two superposed water-tube sections, the front end of the lower section being extended forwardly beyond that of the upper section, a fire-tube section 125; surmounting the aforesaid water-tube sections, a water-leg depending from the rear end of the shell of the fire-tube section and establishing communication between said shell and the rear ends of the water-tube sec- 130

tions, a water-saddle communicating with the front end of the shell of the fire-tube section and with the front end of the upper water-tube section, a header communicating with the front end of the lower water-tube section, and a series of circulating-pipes establishing communication between said header and the shell and saddle of the fire-tube section respectively, substantially as set forth.

4. A boiler comprising two superposed water-tube sections, a fire-tube section surmounting the same, a water-leg depending from the rear end of the fire-tube section and establishing communication between said section and the adjacent ends of the water-tube sections, a water-saddle establishing communication between the front of the fire-tube section and the upper water-tube section, a header into which the front end of the lower water-tube section leads, circulating-tubes establishing communication between the header and the saddle and the front of the fire-tube section respectively, a partition-wall formed in connection with the lower water-tube section and extending a suitable distance rearwardly, a partition-wall formed in connection with the upper water-tube section for substantially the full length of the latter, and a smoke box or flue leading from the rear of the fire-tube section, substantially as set forth.

5. In a boiler, an upper fire-tube section, a lower water-tube section, an intermediate water-tube section, a rear water-leg depending from the fire-tube section and establishing communication with the rear ends of the water-tube sections, the latter being disposed in substantially parallel planes and inclining forward and upward toward the fire-tube section, a front water-saddle establishing communication between the fire-tube section and the intermediate or upper water-

tube section, the lower water-tube section extending forwardly beyond the front of the fire-tube section, a header at the front upper end of the lower water-tube section, and a series of circulating-pipes connecting the header with the fire-tube section and tapping the latter at a point or plane above the upper end of the intermediate or upper water-tube section, substantially as set forth.

6. In combination with a boiler-furnace having a fire-box and bridge-wall, a boiler comprising a lower water-tube section, an upper water-tube section, a fire-tube section surmounting the aforesaid sections, means for establishing communication between the several sections, a partition-wall formed in connection with the lower water-tube section and extending a suitable distance rearwardly beyond the bridge-wall, a partition formed in connection with the upper water-tube section whereby a conduit is formed between said partitions for the passage of the combustion products, said conduit communicating with one end of the fire-tube section, substantially as set forth.

7. In a boiler, an upper fire-tube section, a lower water-tube section, an intermediate or upper water-tube section spaced therefrom and forming a conduit therewith, a smoke-box at the rear end of the fire-tube section, means for directing the combustion products rearwardly along the base of the lower water-tube section, thence forwardly through said conduit into the front end of the fire-tube section, thence rearwardly through the fire-tube section into the smoke-box, substantially as set forth.

In testimony whereof I affix my signature in presence of two witnesses.

tions, a water-saddle communicating with the front end of the shell of the fire-tube section and with the front end of the upper water-tube section, a header communicating with the front end of the lower water-tube section, and a series of circulating-pipes establishing communication between said header and the shell and saddle of the fire-tube section respectively, substantially as set forth.

4. A boiler comprising two superposed water-tube sections, a fire-tube section surmounting the same, a water-leg depending from the rear end of the fire-tube section and establishing communication between said section and the adjacent ends of the water-tube sections, a water-saddle establishing communication between the front of the fire-tube section and the upper water-tube section, a header into which the front end of the lower water-tube section leads, circulating-tubes establishing communication between the header and the saddle and the front of the fire-tube section respectively, a partition-wall formed in connection with the lower water-tube section and extending a suitable distance rearwardly, a partition-wall formed in connection with the upper water-tube section for substantially the full length of the latter, and a smoke box or flue leading from the rear of the fire-tube section, substantially as set forth.

5. In a boiler, an upper fire-tube section, a lower water-tube section, an intermediate water-tube section, a rear water-leg depending from the fire-tube section and establishing communication with the rear ends of the water-tube sections, the latter being disposed in substantially parallel planes and inclining forward and upward toward the fire-tube section, a front water-saddle establishing communication between the fire-tube section and the intermediate or upper water-

tube section, the lower water-tube section extending forwardly beyond the front of the fire-tube section, a header at the front upper end of the lower water-tube section, and a series of circulating-pipes connecting the header with the fire-tube section and tapping the latter at a point or plane above the upper end of the intermediate or upper water-tube section, substantially as set forth.

6. In combination with a boiler-furnace having a fire-box and bridge-wall, a boiler comprising a lower water-tube section, an upper water-tube section, a fire-tube section surmounting the aforesaid sections, means for establishing communication between the several sections, a partition-wall formed in connection with the lower water-tube section and extending a suitable distance rearwardly beyond the bridge-wall, a partition formed in connection with the upper water-tube section whereby a conduit is formed between said partitions for the passage of the combustion products, said conduit communicating with one end of the fire-tube section, substantially as set forth.

7. In a boiler, an upper fire-tube section, a lower water-tube section, an intermediate or upper water-tube section spaced therefrom and forming a conduit therewith, a smokebox at the rear end of the fire-tube section, means for directing the combustion products rearwardly along the base of the lower water-tube section, thence forwardly through said conduit into the front end of the fire-tube section, thence rearwardly through the fire-tube section into the smoke-box, substantially as set forth.

In testimony whereof I affix my signature in presence of two witnesses.
